UNITED STATES PATENT OFFICE.

SOLOMON WILE, OF ROCHESTER, NEW YORK.

SLICING-MACHINE.

1,393,868.

Specification of Letters Patent. Patented Oct. 18, 1921.

Application filed August 25, 1920. Serial No. 405,991.

To all whom it may concern:

Be it known that I, SOLOMON WILE, a citizen of the United States, and resident of Rochester, in the county of Monroe and State of New York, have invented certain new and useful Improvements in Slicing-Machines, of which the following is a specification.

The present invention relates to slicing machines and an object thereof is to provide an improved clamping means for the material to be sliced. A further object of the invention is to provide a guard for the knife which will permit the ready cleaning of such knife. Another object is to provide a movable member for guarding the effective cutting portion of the knife during non-use. A still further object is to provide a stripping device for the knife which may be utilized as a guard for the effective cutting portion of the knife when the machine is not in use.

To these and other ends the invention consists of certain parts and combinations of parts, all of which will be hereinafter described, the novel features being pointed out in the appended claims.

In the drawings:

Figure 1 is a plan view of a slicing machine embodying the present improvements;

Fig. 2 is a view in side elevation;

Fig. 3 is a detail view of the clamping device;

Fig. 4 is an enlarged view of the under side of the clamping bar;

Fig. 5 is an end view of the clamping bar;

Fig. 6 is a section on the line 6—6, Fig. 1;

Fig. 7 is a fragmentary horizontal sectional view showing the guard in open position;

Fig. 8 is a fragmentary side view showing the guard in open position;

Fig. 9 is a detail view of the stripper in the position in which it guards the effective cutting portion of the knife;

Fig. 10 is a similar view at right angles to that shown in Fig. 9;

Fig. 11 is a detail view showing the manner in which the stripper interlocks with the segmental guard at its end; and

Fig. 12 is a detail view of the stripper in stripping position.

Referring more particularly to the drawings, 1 indicates the main frame which has preferably a hook portion 2 at one side adapted to engage over the edge of a sup-

port 3 to hold the machine to such support, a thumb screw 4 being mounted in the hook portion to clamp the frame to the support 3. The frame 1 has a shaft 5 journaled thereon and carrying a cutter 6 at one end, said cutter preferably being in the form of a disk with a peripheral cutting edge. The shaft also has at its opposite end a crank handle 7 by which the shaft and the cutter are turned.

Mounted to move on the frame 1 transversely of the shaft 5 is a carriage 8, said carriage having guiding rods 9 thereon guided at 10 in the frame 1. The carriage also has a rack 11 on its under side which meshes with a pinion 12 on the shaft 5 so that as the shaft 5 is turned, the carriage will be moved, the movement taking place in one direction as the shaft is turned in one direction, and in the other direction with the reversal of the rotation of the shaft. The carriage 8 also has guides 13 on the upper face thereof and these guides are engaged by a table or carriage 14 which moves toward and from the plane of operation of the cutter 6. Movement of the carriage 14 on the carriage 8 may be effected through a lever 15 which is pivoted at 16 to the under side of the carriage 8 and has pivoted thereto at 17 a tooth lever 18, the teeth of which are adapted to coöperate with a tooth 19 secured to the under side of the carriage 14. A spring 20 connects the lever 18 with the lever 15 and a spring 21 connects the lever 15 with the carriage 8. The lever 15 coöperates with a fixed abutment on the main frame 1 as the carriage reaches the end of its movement just prior to the cutting action, thus causing the lever 18 to be shifted

80 85 90 95 100 105 110

and through its engagement with the tooth 19, to shift the carriage 14 on the carriage 8. The amount of this movement may be determined by an adjustable stop 22 which is mounted on the carriage 8 and coöperates with an end 23 on the lever 15. Movement of the lever 18 out of coöperation with the tooth 19 to permit the carriage 14 to be moved away from the plane of the cutter may be effected by the end 24 of the lever 18. No claim is made *per se* in this application to the hereinbefore described parts.

One of the features of this invention is the means for clamping the material to the carriage 14. This means comprises a non-circular post 25 projected upwardly from the carriage 14 near that edge thereof ad-

adjacent the cutter 6 and having an upper screw threaded portion 25^a on which a thumb nut 25^b operates. On this post operates a clamping bar 26 which has a sleeve 27 at one end fitting loosely on the post, the opening through the sleeve being of substantially the same cross section as that of the post. The under side of the clamping bar is provided with a knife edge 28 extending longitudinally of said bar, this edge being substantially over the edge of the carriage 14 which is nearest the cutter. In order to hold the material, the latter is placed upon the carriage 14 and the clamping bar is moved downwardly on the post 25 to compress the material. The thumb nut 25^b is then turned to hold the bar in its adjusted position. The knife edge with the adjacent edge of the table 14 thus holds the material against movement on the carriage 14 during the cutting action.

Still another feature of this invention is the guard for the knife edge which comprises a ring segment 29 preferably hinged at 30 to swing about a horizontal axis below the lowermost portion of the knife, thus permitting the ring segment to swing outwardly and downwardly away from the knife and expose the latter for cleaning. A latch 31 is pivoted at 32 to the frame which is adapted to swing outwardly below the knife and engage with the guard 29 to hold the latter in its upright or guarding position. The segmental ring guard exposes that portion of the knife which operates on the material being cut, one end of the segment being below the plane of movement of the table or carriage 14 and the other end being above such plane.

With the end in view of providing a guard for the exposed portion of the knife when the latter is not in use and for stripping the material from the knife as the latter cuts the material, there is provided a member 33 which is pivoted at 34 to that end of the ring segment below the plane of movement of the table or carriage 14, its upper end being adapted to be connected with the end of the segment above the carriage 14. To permit this connection it is preferred to provide the member 33 on its inner face with two lugs 35 spaced apart a distance sufficient to receive the upper end of the guard 29 between them as shown in Figs. 9 to 11, there being sufficient resiliency in the member 33 and link 29 to permit the parts to be snapped into and out of interlocking relation. This member 33 also serves to strip the material from the rotary knife 6 and to this end it is provided with a rib or portion 36 which will bear closely against the outer face of the knife when the member 33 is in lowered position as indicated in dotted lines in Fig. 2. This lowered position may be maintained by providing an

abutment 37 on the member 33 for coöperating with an abutment 38 on the ring 29.

The detail construction of the machine is immaterial so far as this invention is concerned. In this instance, when the shaft 5 is turned in one direction, the carriage 8 shifts in one direction and the reversal of the movement of the shaft reverses the movement of the carriage 8. Just before the carriage 8 starts on its movement to carry the material toward the knife, the carriage 14 is automatically shifted a desired distance toward the plane of the knife in order to carry the material into the path of the knife. The material is held firmly by the clamp on the carriage 14. The guard is pivoted to permit the cleaning of the knife and a movable member is provided for the effective cutting portion, said member being movable to a position where it will act as a stripper for the knife.

What I claim as my invention and desire to secure by Letters Patent is:

1. A slicing machine comprising a frame, a cutter movable on the frame, a carriage for supporting the material to be sliced movable transversely of the plane of operation of the cutter, and a clamping bar mounted on said carriage and having a knife edge for coöperating with the material on the carriage, said knife edge being situated substantially over the forward edge of the carriage so that the edge of the carriage cooperates with the knife edge to hold the material.

2. A slicing machine comprising a rotary cutter, and a segmental guard for the cutter formed to expose the effective cutting portion of such cutter and hinged at its lower edge to swing away from said cutter.

3. A slicing machine comprising a rotary cutter, a guard for the cutter arranged to expose a portion thereof for cutting, and a member movable to expose and to cover the portion of the cutter which is exposed by the guard.

4. A slicing machine comprising a rotary cutter, a guard for the cutter arranged to expose a portion of the cutter for a cutting operation, and a stripper for the cutter movable to cover that portion of the cutter which is exposed by the guard.

5. In a slicing machine, a rotary cutter, a ring segment acting as a guard for the cutter and exposing a portion thereof, and a member pivoted to one end of the ring segment and adapted to coöperate with the other end of the ring segment to cover the exposed portion of the cutter.

6. A slicing machine comprising a rotary cutter, a ring segment arranged to act as a guard for the cutter and to expose a portion of said cutter for the cutting operation, and a member pivoted to one end of the ring segment and adapted to interlock with the

other end of the ring segment to cover that portion of the cutter exposed by the ring segment, said member being movable to a position where it will act as a stripper for the material cut by the cutter.

5 7. A slicing machine comprising a rotary cutter, a ring segment acting as a guard for the cutter and exposing a portion of the cutter for a cutting operation, a stripper piv-

oted to one end of said ring segment and adapted to interlock with the other end of said ring segment, said stripper in one position acting to expose the cutter and to strip the cut material from the latter, and in the other position acting to cover the exposed 15 portion of the cutter.

SOLOMON WILE.
